HEAD-BAR BRACKET FOR VENETIAN
BLINDS

Hans K. Lorentzen, Montclair, N. J.

Application May 17, 1938, Serial No. 208,339
Renewed March 22, 1939

10 Claims. (Cl. 156—17)

This invention relates to brackets for mounting the head-bars of Venetian blinds. In my U. S. Patent No. 2,083,334, issued June 8, 1937, I have explained that it is desirable to provide mounting brackets of such construction that the same brackets can be used to mount the head-bar either within a window frame or across the face of the frame; also, to provide a construction such that the brackets are reversible, in the sense that any bracket may be used for either right- or left-hand mounting.

The present invention aims to accomplish the ends referred to, in a structure of great simplicity, the parts whereof may be easily and cheaply made as metal stampings, and such that they may be assembled and disassembled for shipment or to meet the exigencies of right- or left-hand mounting without requiring any operation much more difficult than the insertion of a key in a keyhole.

Other features, objects and advantages of the invention will become apparent by reference to the following detailed description of the accompanying drawing illustrating the same.

In the accompanying drawing, in which I have shown an embodiment of the invention in the form as at present preferred:

Fig. 1 is an isometric view of a complete bracket embodying the invention;

Fig. 2 shows a head-bar mounted on a complete bracket such as shown in Fig. 1, installed and with its parts arranged as a right-hand bracket. The view shows the bracket primarily in side elevation, with the head-bar and window frame indicated in vertical section. The mounting shown is known in the trade as an "outside" mounting, i. e., the bracket is mounted on the front or face of the window jamb;

Fig. 3 is in general a front elevation, showing much the same parts as Fig. 2. Again the bracket is arranged as a right-hand bracket. The mounting is what is known in the trade as an "inside" mounting, i. e., the bracket is on the side of the window jamb;

Fig. 4 is an enlarged sectional view taken on the line 4—4 of Fig. 1, certain parts of the bracket being omitted. In dot-dash lines the view shows how the head-bar clamp is applied to and removed from the bracket-body; and

Fig. 5 is a detail vertical sectional view showing the bracket used with a head-bar that is notched in a manner different from the head-bars shown in Figs. 2 and 3.

Referring to the numerals on the drawing, 6 designates as a whole a one-piece sheet metal

stamping, having a planar body 1 formed with legs 8 and 9 which are of equal length and disposed at right angles to each other. Wings 10, 10', 11, and 11' are formed integrally with the body 1, and project at right angles to the body 5 on the same side thereof. The pair of wings 10 and 10' on leg 8 roughly defines a right angle with the pair of wings 11 and 11' on leg 9; and the stamping as a whole is symmetrical about the line that bisects the said right angle. These 10 wings are all perforated as at h, to receive screws 12 for mounting the bracket on the front or face of a window jamb as shown in Fig. 2. In case the bracket is to be mounted on the side of the window jamb the screws 12 will be inserted as 15 shown in Fig. 3 through holes 13 in the bracket body 1 (see Figs. 1 and 2).

It will be apparent that the bracket can be utilized for either right-hand or left-hand mounting. In the former case, as shown in Fig. 2, 20 the wings 11 and 11' are available for attachment to the upright front surface of a window jamb, while the wings 10 and 10' serve to support the head-bar 14. When the stamping is to be mounted left-hand on the front of a window 25 jamb it is partially rotated about its axis of symmetry, so that the wings 11 and 11' become the head-bar support, while the wings 10 and 10' are secured to the window jamb. In the case of "inside" mounting such as shown in Fig. 3, the holes 30 13 will be used for attaching the bracket to the side of the jamb, regardless of whether the bracket be positioned right-hand or left-hand.

Guideways for the reception and control of a head-bar clamp are provided in the bracket on 35 either side of the symmetry axis and at right angles to each other. Since the two guideways are alike, only one will be described.

Between wings 10 and 10' there is a depressed metal portion 15 which projects laterally from 40 body 1 parallel to wings 10 and 10'. Located perpendicularly to portion 15 is a portion 15a which is displaced sidewise from the bracket body 1, this being made possible by metal of the bracket body being cut out as at 16. Below opening 16 the bracket body is provided with another opening 17, aligned and parallel with opening 16, the lower boundary of opening 17 being a pair of tongues 18, 18 whose free ends are 45 spaced apart and bent away from the bracket body in the direction of the extension of portion 15a from the body. Between the openings 16 and 17 there remains a strip 19 in the plane of body 1 and provided midway of its length with a hole 20.

Adapted for cooperative relation with either one of the guideways just described is a clamp member comprising a length or strip of metal 21. At one end this has a bent-over clamp portion 22, and at the other end it has portion 23 bent away from the strip parallel to and in the same direction as clamp portion 22. The portion 23 constitutes a finger-piece and is connected to the main body of the strip 21 by a reduced neck 24. Spaced along the length of strip 21 is a plurality (two are shown) of punch marks 25 forming dimple projections; and in addition a half-round projection 26.

In use, the clamp member is brought into assembled relation with the bracket by inserting the finger-piece end 23 through one or the other of the openings 16 according to whether the bracket is to be used for right- or left-hand mounting, the bent-over end portions 22 and 23 being directed inwardly towards the wings of the bracket. This insertion is made as indicated in dot-dash lines in Fig. 4. The part 15 of the bracket is depressed below the general plane of the wings 10 and 10' sufficiently to permit the 25 swinging movement necessary to insert the clamp member in the guideway. Portion 15a and the tongues 18 are each displaced sufficiently from the body 7 to permit the clamp strip 21 to slide freely past them over the bridge strip 19 until the lowermost one of the circular projections 25 frictionally engages the strip 19 and snaps into the hole 20. If continued pressure is exerted on the clamp strip in a downward direction, the projection 25 will leave its seat in hole 20, and the next above projection 25 will snap into the hole 20. The limit of the downward movement is reached when the stop projection 26 engages the upper edge of strip 19. The clamp strip with its finger-piece 23 is enabled to pass the tongues 18 because the reduced neck portion of the finger-piece at its junction with the main length of the strip is of less width than the space between the free ends of the tongues.

It is believed that the manner in which the 45 brackets support and retain the type of head-bar shown in Figs. 2 and 3 will be clear from the drawing. At present such commercial head-bars are one and one-eighth or seven-eights inches tall. The dimples 25 are spaced from clamping 50 portion 22 in relation to these standard heights. In locating the brackets on the window jamb, these dimples are utilized to space clamp 22 as shown in dot-dash lines of Fig. 3 so that portion 22 may be placed against the top of the window 55 frame and act as a gage to appropriately locate the bracket. After the bracket has been so located, the mounting screws are inserted.

In Figs. 2 and 3 the head-bar has in its top surface a longitudinal groove 30 which receives the clamp member 22 and limits its downward movement. In Fig. 5, the clamp member enters a slot or slot-like cavity 31 in the vertical end wall of the bar. This slot is incapable of limiting the downward movement of the clamp, but projection 26 arrests the clamp in retaining relationship to the head-bar.

I claim:

1. A bracket comprising a planar body of sheet metal having two diverging legs perpendicular to each other; wings integral with and defining the outer boundaries of the legs, the wings extending perpendicularly to the body on the same side thereof; a guideway formed in each leg; and a clamp member insertable into and removable from either of the guideways.

2. A bracket comprising a planar body of sheet metal having two diverging legs perpendicular to each other; wings integral with and defining the outer boundaries of the legs, the wings extending perpendicularly to the body on the same side thereof; a guideway formed in each leg; and a clamp member insertable into and removable from and adjustable in either of the guideways.

3. The device of claim 1, in which each guideway comprises a depressed portion of the body with an opening adjacent to it, and a pair of confronting tongues spaced from said depressed portion, the tongues extending away from the body with their free ends spaced apart; and in which the clamp member is an elongated strip having both ends bent over in the same direction, one of the bent-over ends being connected to the strip by a reduced neck that is narrower than the space separating the ends of the aforesaid tongues.

4. The device of claim 2, in which each guideway comprises a depressed portion of the body with an opening adjacent to it, a second opening spaced from the first, and portions depressed from the general plane below the second opening; and in which the clamp member is an elongated strip slidable between the body on one side and the depressed portions on the other side, the clamp member and the body having cooperating portions for resiliently holding the clamp member in one of a plurality of positions to which it may be slid.

5. The device of claim 2, in which each guideway comprises a depressed portion of the body with an opening adjacent to it, a second opening spaced from the first, a pair of confronting tongues immediately below the second opening, the tongues extending away from the body with their free ends spaced apart; in which the clamp member is an elongated strip having both ends bent over, one of the bent-over ends being connected to the strip by a reduced neck that is narrower than the space between the tongue ends; and in which the clamp member and the portion of the body lying between said openings have cooperating portions for resiliently holding the clamp member in one of a plurality of positions to which it may be slid.

6. A Venetian blind head-bar bracket comprising: a sheet-metal bracket stamping having a flat body portion and a guideway integral with said body portion, the guideway comprising sheet-metal elements spaced lengthwise of the guideway and pressed out from the plane of said flat body portion to slidably hold a keeper against the remaining metal of the flat body portion, at least one of said sheet-metal elements being in the form of a pair of confronting tongues with their ends spaced apart; and a keeper removable from and insertable into said guideway, the keeper comprising a strip of metal having both ends bent over in the same direction and one of the bent over ends being connected to the strip by a reduced neck portion adapted to pass between said confronting tongues for insertion of the keeper into the guideway and removal of the keeper from the guideway.

7. A Venetian blind head-bar bracket comprising: a sheet-metal bracket stamping having a horizontal bar-supporting flange and also having a vertical flat body portion and a guideway integral with said body portion, the guideway comprising a pair of confronting tongues pressed out from the plane of said flat body portion and having their free ends spaced apart; and a keep-

er insertable into said guideway and slidable therein, the keeper comprising a strip of metal having both ends bent over in the same direction, one end having a zone of lesser width than the strip, said zone being adapted to pass between said confronting tongues for insertion of the keeper into the guideway.

5. A head-bar bracket for Venetian blinds, comprising: a planar body of sheet metal having two diverging leg portions perpendicular to each other; spaced wings integral with and defining the outer boundaries of the leg portions, the wings extending perpendicularly of the body on the same side thereof, and there being two of the 10 wings on each leg portion with a space between them adjacent to the center of the leg; a head-bar retaining member having a vertical sliding portion positioned adjacent to said planar body and having a laterally extending finger adapted to be moved downwardly into a groove in the 15 top of the head-bar, said retaining member being shiftable from one leg portion of said body to the other whereby the bracket may be mounted either right-hand or left-hand; and means to 20 slidably support said retaining member on either of said leg portions with said vertical portion of the retaining member in position to slide between the two wings defining the outer boundary of the leg portion.

25 9. A head-bar bracket for Venetian blinds, comprising: a planar body of sheet metal having two diverging leg portions perpendicular to each

other; a plurality of spaced wings integral with and defining the outer boundaries of each of the leg portions, the wings extending perpendicularly of the body on the same side thereof; a head-bar retaining member having a vertical sliding portion positioned adjacent to said planar body and having a laterally extending finger adapted to be moved downwardly into a groove in the 10 top of the head-bar, said retaining member being shiftable from one leg portion of said body to the other whereby the bracket may be mounted either right-hand or left-hand; and means to 15 slidably support said retaining member on either of said leg portions with said vertical portion of the retaining member in position to slide between the spaced wings defining the outer boundary of the leg portion.

10. A head-bar bracket for Venetian blinds, comprising: a planar body of sheet metal having two diverging leg portions perpendicular to each other; wings integral with and defining the outer boundaries of the leg portions, the wings extending perpendicularly of the body on the same side thereof; a head-bar retaining member having a vertical sliding portion positioned adjacent to said planar body, said retaining member being shiftable from one leg portion of said body to the other whereby the bracket may be mounted either right-hand or left-hand; and means to 20 slidably support said retaining member on either of said leg portions.
